UNITED STATES PATENT OFFICE.

CHARLES H. HOWARD, OF CLIFTONDALE, AND LEWIS SHARP, OF ATTLEBORO FALLS, MASSACHUSETTS, ASSIGNORS TO PAPER PRODUCTS MACHINE COMPANY, OF BOSTON, MASSACHUSETTS, A CORPORATION OF MASSACHUSETTS.

FABRIC OR PAPER REENFORCING MACHINE.

Application filed June 24, 1920, Serial No. 391,433. Renewed August 14, 1923.

To all whom it may concern:

Be it known that we, CHARLES H. HOWARD and LEWIS SHARP, a citizen of the United States and a subject of King George V of Great Britain, respectively, residing at Cliftondale, county of Essex, and Attleboro Falls, county of Bristol, respectively, State of Massachusetts, have invented an Improvement in Fabric or Paper Reenforcing Machines, of which the following description, in connection with the accompanying drawings, is a specification, like characters on the drawings representing like parts.

This invention relates to machines for reenforcing fabrics by filaments running longitudinally thereof. The filaments to which reference is made may be of various kinds, but more particularly the present invention has reference to the application of unspun fibres to the fabric to be reenforced.

Various kinds of unspun fibres may be used but the present invention relates more particularly to means for applying unspun fibres of long staple to the fabric to be reenforced, such, for example, as sisal, flax, ramie, hemp, and other forms of fibres, but of course it will be understood that in certain aspects the invention is not limited thereto.

The unspun fibres are usually prepared in roving or sliver form. That is, the fibres are reclaimed from the woody material which naturally adheres to them, or other undesirable foreign substance, and are then formed into long untwisted ropings or rovings, or slivers, the terms last mentioned being variously applied, according to either the character of the fibres or the colloquial use. The term "roving" will hereinafter be used to designate these untwisted ropings of fibre, and while the term will have more particularly in view, such ropings of fibres of long staple, it is to be understood that in certain aspects of the invention the length of the fibres themselves may vary. Indeed, in some cases, it may be desirable to mix long and short staple fibres for application to the fabric to be reenforced, so that the term "roving" as hereinafter employed, is used in its generic sense.

One of the problems presented in applying the fibres of rovings to the fabric to be reenforced, is the difficulty experienced in

laying the fibres in an economically thin sheet, and in parallel relation on the fabric to be reenforced. It has been found, however, that by feeding rovings or moving them from a source of supply and then distributing them in sheet form, the fibres, especially of long staple, may be adhesively secured to the surface of the fabric in substantially parallel relation longitudinally thereof. To insure that the fibres of roving shall be distributed with substantial equality throughout the width of the fabric or paper to be reenforced, the fibres of the rovings are flattened or made into a sheet-like form, and then the sheet of fibres is attenuated and the fibres adhesively secured to the surface of the fabric or paper in substantial parallelism, and in many cases, while they are under longitudinal pull or tension.

An important feature of the present invention, therefore, consists of means for feeding rovings for application to a fabric to be reenforced, and applying the unspun fibres in an attenuated sheet form to the surface of the fabric or paper.

In carrying this feature of the invention into effect, the rovings in the present invention are fed by feeding means and spread out or distributed into sheet form between the feeding means and the point of application to the fabric, and either at or before the time of its application to the fabric, the sheet of fibres is drawn out or attenuated. It has been found in practice that the attenuation of the sheet of unspun fibres may be effectively accomplished by running the paper-feeding means at a higher rate of speed than the rate of delivery of the fibres to the fabric, the consequence being that the ends of the fibres which are grasped by the adhesive surface of the paper as they are fed toward it, will be pulled by the adhesive surface of the paper lengthwise and drawn out or pulled from the associated fibres which have not yet reached the adhesive surface of the paper, the consequence being that the sheet of fibres will be attenuated and the fibres themselves will be laid in substantial parallelism longitudinally of the fabric or paper to be reenforced.

In reenforcing fabrics by unspun fibres it is desirable that the reenforcing unspun fibres be applied under lengthwise tension.

so that a force tending to tear or rupture the fabric will be resisted by the taut or tensioned fibres.

Another important feature of the present invention, therefore consists of means for applying the reenforcing unspun fibres to the fabric or paper under lengthwise tension. This is accomplished by exerting a holding or retarding force upon the unspun fibres as they are drawn forward by and applied to the moving fabric or paper.

It has been found advisable, though not always essential in practice, to draw out or partially attenuate the sheet of fibres before the sheet is presented to the fabric or paper to be reenforced; and to then exert a retarding or holding force upon the fibres to tension them as they are drawn forwardly from the associated fibres by the paper to which they are adhesively secured. An effective means to this end has found its response in a combing device which is preferably placed between the feeding means for the rovings, and the point of delivery of the fibres to the adhesive surface of the paper. It may be desirable to move the comb somewhat faster than the feed rolls, and to move the paper-feeding rolls at a higher rate of speed than the comb, the consequence being that the sheet of fibres will be attenuated and a substantially uniform parallelism of the fibres be secured as they are adhesively placed upon the fabric or paper.

When the fibres are delivered to the adhesive surface of the fabric or paper to be reenforced, it is desirable that they be gradually detached from their connection with the comb as they move toward the point of delivery of the fibres to the fabric or paper; and to this end the present invention provides means for partially disengaging and then fully disengaging the fibres from the comb as the comb moves toward the point of delivery of the fibres. The effect of this is that the pull of the paper or fabric upon the ends of the fibre, especially where the fibre passes between the nip of two paper-feeding rolls, does not rupture or break the fibres, but permits the fibres to be drawn out, attenuated, and placed under lengthwise tension without rupture.

The rovings are usually formed in bales and placed upon the market. The bales may be of various forms and shapes, but in any case, the association of a large number of such bales or cases containing the rovings, has been a problem of difficulty because the rovings themselves are to be laid side by side in substantially parallel relation as they pass to and beyond the feeding means, and consequently, they occupy little transverse space as compared with the space occupied by the bales or cans or roving. The solution of this problem has led to the development of a novel form of means for enabling

the feeding means to move the rovings from sources of supply remote therefrom without, at the same time, attenuating the rovings, drawing them out, or breaking them by the feeding pull thereon. An important feature of the present invention, therefore, consists of roving feeding means and means between the roving feeding means and the sources of supply of the rovings to enable the pull or draft upon the rovings to be extended substantially to the source of supply without attenuating the rovings, or drawing them out, or breaking them.

In carrying this feature of the invention into practical effect, the rovings are led from the source of supply through devices such as idle rolls, which are arranged between the roving feeding means and the sources of supply at less distance apart than the average length of the fibres composing the rovings. The effect is that the roving feeding means acts upon fibres which extend to and slightly beyond the nip of the first pair of rolls, and consequently pull these fibres longitudinally and rotate the rolls. The adjacent fibres adhering to those that are being pulled, will follow along into the nip of the rotating rolls which thereupon cause a draft on these fibres which extend back to the next pair of rolls, and so on, the draft continuing throughout an indefinite series of rolls or other draft-transmitting devices so that the rovings while being fed from the sources of supply remote from the feeding means, are not drawn out or elongated, or broken.

Various novel features and new combination of parts will be hereinafter described in connection with the accompanying drawings which illustrate one good, practical form or embodiment of the invention, it being understood, of course, that the details may be varied within wide limits, without departing from the true invention, as defined by the claims.

In the drawings:—

Figure 1 is a side elevation of a machine embodying features of the present invention, some of the parts being broken away or shown in section to illustrate parts beyond;

Fig. 2 is a plan view of one good, practical form of means for supplying rovings from sources of supply to the feeding means without elongation or breaking of the rovings;

Fig. 3 is a side elevation, parts being in section, of the construction shown in Fig. 2;

Fig. 4 is an enlarged perspective detail with parts broken away, showing more particularly the roving feeding means, one good manner of forming the rovings into a sheet, and the comb or partial attenuating means;

Fig. 5 is a detached detail showing one of the comb bars, its combs or teeth, and the means for detaching the fibres from the teeth of the comb.

Fig. 6 is a perspective view showing a slightly modified form of the means for forming the rovings into a sheet, and also illustrating the effect upon the sheet of 5 fibres and its attenuation by the comb and the rapidly-moving fabric or paper to which the fibres are delivered.

The present invention will be described more particularly with reference to the reinforcement of paper or paper strips by 10 the application thereto of the unspun fibres, preferably of long staple, but it will be understood, of course, that the character of the fabric to be reenforced may be varied, and that the adhesive which is applied to the surface of the paper or fabric 15 may be formed of appropriate composition or mixture such as asphaltum.

The machine frame is suitably constructed for supporting the operative parts 20 and comprises the side frames 1 which may be tied together by the usual cross-ties or struts for bracing the frame. The fabric or paper which is to be reenforced may be taken from a suitable supply. This may 25 be of any character, but in the present instance the paper is taken from a roll and moved longitudinally through suitable guiding and directing means as the unspun fibres are delivered thereto. It may sometimes be desirable to have the fibres enclosed between two or more sheets or strips 30 of paper, in which case the desired number of strips may be appropriately furnished from suitable supplying and guiding means. In the present instance of the invention, the machine frame comprises end supports 2 on which are suitably mounted the paper rolls 3 and 4 from which the paper to be 35 reenforced is drawn. The paper from the roll 3 passes over the guide rolls 5 and 6 mounted in suitable supports and then between the rolls 7 and 8, the latter of which dips into a tank 9 which extends transversely of the paper and contains an adhesive. In the present instance, the adhesive is black asphaltum which is preferably kept in a heated condition by suitable 40 circulating pipes for steam or other media. As the paper strip from the roll 3, which will be identified as the paper strip *a* passes between the rolls 7 and 8, a coating of adhesive or asphaltum is applied to one surface thereof, and then the paper strip *a* 45 passes about the paper feed roll 10, which is mounted in a column 11 rising from the machine frame. The paper feed roll 10 may be appropriately driven from any suitable source of power, as by belting connection with an overhead or line shaft. Where 50 a second strip of paper is to overlie the first strip, such as the strip of fabric or paper *b*, it is passed about a guide roll 12 conveniently supported by the columns 11, 55 one at each side of the machine, and then

the paper strip *b* passes downwardly as indicated by the arrows, beneath a feed roll 13, where it is placed upon the adhesive surface of the strip *a*, as will presently appear. The feed rolls 10 and 13 70 rotate in a direction indicated by the arrows, and after the two strips *a* and *b* have been drawn together between the nip of the rolls 10 and 13, where the reenforcing fibres are applied, as will presently appear, 75 the two paper strips now joined together with the fibres adhesively secured between them pass around a roll 14 mounted in the columns 11. The rolls 10, 13 and 14, may be geared together if desired, and one of them may be driven from an overhead line shaft by suitable means such as the belt 15. The gearing connection between the rows 10, 13 and 14 is indicated in Fig. 1, but, 80 being well understood, the manner of transmitting motion between the rows associated, as herein described, its further illustration herein is not deemed necessary. The fabric or paper feeding rolls may be forced together into a proper biting or nipping 85 relation by a hand-wheel 16, which is connected to a screw 17 threaded into suitable boxes carried by the feed rolls. This manner of forcing the rolls into a biting or gripping relation is well understood in the art, and there is nothing new therein so 90 that the details of this feature of the present mechanism are not further disclosed, because it is well understood in the art.

The two paper strips having been brought together at the nip of the feed rolls 10 and 13, and the strips having been reenforced by the application of fibres adhesively secured thereto, the new composite strip *c*, Fig. 1, is moved in the direction of the arrow, and wound upon a suitable roll 18. The roll 18 may be variously located and have appropriate means for connecting and disconnecting it with its supports so that when loaded, it may be conveniently removed, and another roll substituted. The roll 18 is driven at appropriate speed for taking up the composite fabric as it is produced.

The means thus far described in detail pertains more particularly to the fabric or paper feeding mechanism and the means for applying an adhesive to one surface of one of the strips of fabric or paper, and winding the composite strip upon the receiving roll. It is now appropriate to describe the means for feeding and applying the reenforcing filaments or unspun fibres to the fabric.

Mounted either upon the main machine frame or a separate support provided therefor is the roving feeding or moving means. In the present instance of the invention, the feeding means for the roving consists of two rolls which are preferably fluted and are

driven in appropriate direction for feeding rovings therebetween and delivering them for application to the fabric or paper. In the present instance of the invention, the feeding means consists of the lower fluted feed roll 19, appropriately supported in a bearing 20 and having in driving connection therewith the sprocket wheel 21. The upper fluted feed roll 22 is preferably carried in a bearing mounted in a box 23, whereby the upper fluted feed roll may be adjusted toward and from the lower feed roll 19 by means such as a hand-wheel 24 connected to the threaded adjusting stem 25, substantially as indicated in Figs. 1 and 4. By manipulation of the hand-wheel 24, the bearing box 26 (one at each side of the machine) may be adjusted to vary the relation between the upper and lower fluted feed rolls 22 and 19 to accommodate the character of fibres or rovings to be fed thereby.

The roving feeding means may be driven from any suitable source of power, and in the present instance of the invention the sprocket wheel 21 is actuated by a sprocket chain 27, Figs. 1 and 4, which is driven from a sprocket wheel 28 secured to the transverse shaft 29, Fig. 4. The shaft 29 has secured thereto the worm wheel 30, Fig. 4, which is engaged by a worm 31 carried by a shaft 32 appropriately supported by the bracket 33 adjacent the worm and driven from suitable power-actuated means. In the present instance the worm shaft 32 extends upwardly from the bracket 33 and has a bearing in an overhead hanger 34. At its upper end the worm shaft 32 has a belt pulley 35 which is driven by a belt 36 leading from a line shaft pulley 37.

The means thus far described for operating the roving feeding means constitutes a good, practical form of mechanism, but of course it is to be understood that the present invention is not restricted to the means described, but that other appropriate means may be employed for driving the roving feeding means.

Where the fibres which are to be applied as reinforcing filaments to the fabric are supplied in the form of rovings, such as hereinbefore referred to, they are led to the feeding means from a source of supply more or less remote. Since the rovings are untwisted, they are liable to be drawn out lengthwise and broken by the pull of the roving feeding means. The present invention, therefore, provides means for transmitting the draft of the roving feeding means to the rovings at intervals from the roving feeding means to the source of supply, and the draft-transmitting devices are arranged a distance apart not greater than the length of the longest fibres and preferably at a distance apart substantially equal to the average length of the fibres. The

draft transmitting means may be variously contrived, but in the present instance of the invention, and as a good, practical form of this feature, the draft transmitting means consists of idle rolls, preferably arranged in pairs, and between each pair the rovings are passed so that as the draft upon the long fibres rotates any pair of rolls, its movement transmits to the next adjacent pair of rolls toward the source of supply, a rotating movement which in turn, is transmitted through the fibres extending between that pair of rolls and the next toward the source of supply through the entire series, such that the rovings are not drawn right out or attenuated or broken by the pull of the roving feeding means. In the present instance of the invention, the rovings are taken from cans or receptacles and passed upwardly through a roving-supporting table and between pairs of idle rolls at distances apart less than the average length of the fibres; but it is to be understood with respect to this feature of the invention that while the construction shown and presently to be described constitutes a good, practical form of this feature, as a matter of fact, the rovings might be taken directly from the bales and the bales might be located in any convenient position, even on the floor above, so long as the draft-transmitting means such as the idle rolls, hereinbefore generally described, are arranged to bear upon the rovings at distances apart not greater than the average length of the fibres constituting the rovings.

As indicated in Fig. 1, the first pair of draft-transmitting rolls 38, 39, are at a distance from the fluted drawings rolls 19 and 20 which constitute the roving feeding means less than the average length of the fibres composing the rovings. The second pair of rolls, which are indicated at 40, Figs. 2 and 3, are located a distance from the rolls 38, 39 less than the average length of the fibres composing the rovings; and so with the draft-transmitting rolls 41, 42, 43, 44, 45, each pair of draft-transmitting rolls is located a distance from the adjacent rolls less than the length of the average fibres composing the rovings.

The draft-transmitting rolls are arranged to press upon or rest upon the rovings, and nip the rovings between the bite of the rolls. In the present instance the weight of the upper one of each pair of draft-transmitting rolls is utilized to effect the nip or bite of the rolls upon the rovings. To effect this the upper roll 40, for instance, Fig. 3, is mounted in slotted bearings 46 which permit the roll 40 to rest by its weight upon the rovings and at the same time to yield upwardly to varying thicknesses of rovings. The other rolls of the series may be similarly mounted or they may be mounted in

any suitable manner for causing the rolls or draft-transmitting devices to bite or nip upon the rovings at intervals not greater than the length of the longest fibres constituting the rovings.

The draft-transmitting rolls extend transversely of a table 47 in the present instance of the invention, and below the table are a series of cans or receptacles 48 in which the 10 rovings are wound and from which they are drawn. The table 47 has a series of openings 49 through which the rovings pass upwardly from the receptacles or cans 48; and in order that the rovings, which 15 may be indicated at 50, may lie side by side in appropriate transverse width corresponding to the width of the paper to be re-enforced, the holes 49 in the table 47 are arranged in staggered relation or in the 20 form of an echelon. That is, the holes 49 along each side of the centre of the table 47 are arranged to gradually be nearer the side of the table as they approach the roving feeding means. The consequence is that 25 by leading the rovings through appropriate openings 49 in the table, commencing at the centre as indicated in Fig. 2, a sufficient number of rovings may be arranged side by side for presentation to and draft by the 30 roving feeding means in accordance with the width of the paper to be reenforced. When narrower paper is to be reenforced, the rovings nearer the edge portions of the table or those more remote from the centre 35 of the roving are omitted; and conversely, when wider paper is to be reenforced, additional rovings are added toward the sides of the table.

The table may have its top surface 40 marked appropriately to designate the width of the fabric which is to be reenforced, and correspondingly, the guide holes or guides 49 for the rovings may be appropriately designated to indicate the width of 45 the fabric that is being reenforced when said holes have rovings leading therethrough.

The construction described may be varied. The table and the guiding means for the 50 roving or holes 49 and the draft-transmitting devices may be changed to suit conditions of use, and indeed, it may not always be necessary to employ the table 47 so long as the draft-transmitting devices or rolls 55 40 which transmit the draft of the feeding means throughout the length of the rovings to the sources of supply, prevent the rovings from being elongated or broken between the feeding means and source of 60 supply.

The rovings 50 pass between the nip of the feeding rolls 19 and 22, and are flattened somewhat; but it is preferable before applying the fibres of the rovings to the fabric to be reenforced, to spread the rovings

out or distribute the fibres into a sheet form. This may be done in various ways, and the manner of accomplishing the sheet formation of the rovings after passing through the feeding means, is indicated in 70 Fig. 1, wherein the upright 51 of the machine frame has connected thereto a sheet-forming or spreading bar 52. The sheet-forming or spreading bar 52 is preferably located above the roving feeding means so 75 that the forming sheet may be clearly within the view of the workman, and the edges 53 of the sheet-forming bar are rounded so as to offer frictional resistance to the travel of the fibres. After passing through or between the feeding rolls 19 and 22, the rovings now slightly spread out by the pressure of the rolls upon them, are led upwardly over the sheet-forming or spreading bar 52, as indicated by Figs. 1 and 4, where the 80 fibres will become spread out and distributed laterally into sheet formation, although relatively too thick and massive for application to the fabric or paper to be reenforced. 90

In some cases, after the fibres have been distributed into sheet formation, as hereinbefore described, they may be passed to the nip between the fabric or paper feeding rolls which are preferably driven at much 95 higher speed than the roving feeding rolls, the consequence being that the sheet of fibre will be attenuated and the fibres will be laid in proper thickness and mass on the adhesive surface of the fabric or paper to be reenforced. It is preferable, however, to provide means between the sheet-forming means and the point of delivery of the fibres to the surface of the fabric or paper to be reenforced, for drawing out or preliminarily attenuating the fibres and retarding them against the pull incident to the fibres coming into contact with the adhesive surface of the fabric or paper at the point of application thereof which, in the present 100 invention, is shown as at the nip between the rolls 10 and 13.

The length of the path the fibres travel in passing from the fluted feed rolls 19, 22 to the paper feeding rolls 10, 13 should be 115 greater than the longest fibres fed to the machine. This is desirable, because the fibres cannot be readily pulled forward and attenuated by the rolls 10, 13, or by the combs until the rear ends of the fibres have 120 been released by the fluted rolls. The length of the path the fibres travel can be made as great as desired irrespective of the distance between the fluted rolls 10, 13 and paper rolls 19, 22, by advancing the fibres 125 over a tortuous or indirect path. The spreading bar 52 serves satisfactorily to increase the length of the path of the fibres the desired amount, as will be apparent from Fig. 1, and due to this construction a 130

compact machine is obtained with a resulting economy of floor space.

Between the roving feeding means and the point of delivery of the fibres, is a combining device, the function of which is to carry the sheet of fibres toward the point of delivery and preferably at a somewhat higher rate of speed than the speed of the roving feeding means, and to deliver the fibres to the fabric or paper to be reenforced. A further function of the comb is to exert a retarding effect upon the forward movement of the fibres after they engage the adhesive surface of the fabric or paper so as to cause the fibres to be brought out and the sheet to be further attenuated in order that the proper number of fibres may be laid upon the fabric or sheet in substantially parallel relation under some longitudinal tension.

Mounted in suitable bearings 54 secured to the machine frame, is the comb shaft 55 which carries at each end portion thereof a sprocket wheel 56. Mounted on the shaft 29 adjacent the fabric or paper feeding means is the sprocket wheel 57, one at each end portion of the shaft, as indicated in Fig. 4. Extending between the sprocket wheels 56 and 57 on the respective shafts 55 and 29, is the combing device which, in the present instance of the invention, consists of a series of links preferably in the form of a sprocket chain 58 which passes around the two sprockets 56 and 57, one of such chains being at each side of the machine. The sprocket chain 58 carries a series of comb bars 59, one of which is shown detached in Fig. 5. The comb bars 59 may be secured to the links of the sprocket chain 58 by any suitable means, as for instance, the bolts 60, one at either end of the comb bars. As shown in Fig. 4, the comb bars 59 are preferably secured to link members 61 extending between the pivots 62 of adjoining links of the sprocket. To prevent sagging of the sprocket chain 58 between the sprocket wheels 56 and 57, a trackway 63 is provided, over the top portion of which may run the rolls 64 carried by the sprocket chain.

The comb bars 59 carry a series of teeth or pins which enter the sheet of fibres delivered from the roving feeding means and serve to move the sheet of fibres toward the point of delivery. In the present instance the teeth or pins 65 are conveniently mounted in a metal bar 66 which may be secured to the respective comb bars 59 by suitable means such as the screws 67. The teeth or pins 65 may be arranged in more than one row, if desired, and in the present instance of the invention are shown as formed in two rows. From the construction described it will be apparent that the comb bars travel with the endless carrier in the

endless path prescribed by it, which for purposes of identification in the claims will be referred to as an orbital path.

The sheet of fibres, which may be designated as F, may be confined to the desired lateral spread by means of guides 68, which may be secured adjustably to a supporting bar 69 extending transversely of the machine and secured by appropriate brackets 70 to the machine frame, the construction being such that the width of the sheet of fibres may be made to conform to the width of the fabric or paper to be reenforced.

The sheet of fibres F is guided to the combing device by means of a guide roll 71 Figs. 1 and 4, which may be conveniently supported for idle rotative movement in brackets 72 secured, one at each side of the machine frame. The position of the guiding rolls 71 is such that as the teeth or pins 65 of the comb rise from the lower run of the sprocket chain, they may enter the sheet of fibres and take control thereof and move it toward delivering position.

The position of the shaft 29 is such that the fibres being moved toward the delivery position, will extend into the bite between the fabric or paper feed rolls 10 and 13, which are preferably driven at a higher surface speed than is the comb, the effect being that as the fibres come in contact with the adhesive surface of the fabric or paper which is moving rapidly as compared with the movement of the comb, the sheet of fibres will be further attenuated, the pins or teeth of the comb will retard the pull upon the fibres by the fabric or paper, and cause them to be laid in substantially parallel relation longitudinally of the fabric or paper.

It may sometimes happen that the hold of the teeth or pins 65 upon the sheet of fibre would be too energetic at the moment of delivery of the fibres to the fabric or paper, and it may be desirable at times, therefore, to provide for the release of the fibres from the comb after the sheet has been sufficiently attenuated and the pull upon the fibres has straightened them and laid them substantially parallel. On the other hand, the fibres should not be released from the teeth too quickly, which might result in insufficient attenuation of the sheet and failure to lay the fibres in substantially parallel positions.

Various means may be provided for the desired delivery of the fibres from the comb to the fabric or paper feeding rolls, and one good form of such device is shown as comprising lifter bars or doffers 73, one of which is carried by or preferably associated with each of the comb bars 59 as illustrated in Fig. 5. As shown in Fig. 5, the lifter bars 73 are provided with slots 74 through which extend the guiding studs or screws

75, the construction being such that under the impulse of gravity, the lifter bars 73 will drop to their low position as indicated in Fig. 5, when the comb bars are traveling along the upper run of the comb; and when the comb bars reach the fiber-delivering position, means are provided for lifting the lifter bars or doffers 73 in succession to detach the fibres from the pins or teeth 65 of the comb. In the present instance of the invention, the shaft 29 has mounted thereon the lifter cams 76, one adjacent each end portion of the shaft 29. The cams 76 have the risers 77 which are 15 timed with respect to the travel of the comb bars such that as the comb bars pass about the axis of the shaft 29, the risers of the lifter cams engage the lower edge portion of the lifter bars and lift the bars 20 successively to detach the fibres from the teeth or pins 65 of the comb and permit them to pass with less and less retardation to the nip between the fabric or paper-feeding rolls 10 and 13. The consequence 25 is that the sheet of fibres which may have been attenuated to some extent by the comb, is further attenuated and drawn out, and the fibres laid parallel by the pull of the adhesive surface to which the ends of the 30 fibres are applied.

It may sometimes be desirable to insure that the lifter bars 73 drop to their lower position as the comb bars rise to pass the teeth or pins into the sheet of fibre; and 35 to this end the present invention contemplates a pair of cam depressors 78, Figs. 1 and 4, one preferably at each side of the machine, which act upon the top surface of the lifter bars 73 and forcibly push them 40 downwardly, if they have not already been lowered under the action of gravity.

As will be noticed in Fig. 1, the upper run of the comb is preferably inclined somewhat to the path of movement of the 45 fibres from the comb to the nip of the feeding rolls 10 and 13; and since at the time the fibres are engaged by the adhesive surface of the fabric passing between the feed rolls 10 and 13, they are placed under lengthwise tension or pulled, it may happen 50 at times that they will lift from the pins or teeth of the comb too quickly. To prevent this, the present invention provides a depressor which consists of a pair of 55 discs 79, one at each side of the machine, and mounted on a shaft 80 supported in suitable bearings 81. Extending between the discs are a series of bars 82, Figs. 1 and 4, which are spaced apart; and by rotation of the discs which may be effected 60 by the friction between the sheet of fibres and the bars 82, such bars pass between the rows of pins or teeth of the comb and insure the hold of the teeth upon the sheet 65 of fibres until the sheet has been sufficient-

ly attenuated and the fibres drawn out under the longitudinal pull of the adhesive surface of the fabric or paper.

From the construction thus far described, it will be seen that unspun fibres are moved 70 from a source of supply in the form of rovings by the roving feeding means, and are then spread out into sheet form; that the sheet of fibres is attenuated to a proper degree 75 for the desired reenforcement of the fabric or paper; and the fibres are adhesively secured to the surface of the fabric or paper in parallel or substantially parallel relation. The attenuation of the sheet may be entirely effected by the relative speed of the 80 fabric or feeding rolls and the combing device; but it may be preferable in some cases to assist in the attenuation of the sheet of fibres by utilizing the movement of the comb itself, relative to the feed of 85 the roving feeding means. That is, the roving feeding means will be actuated at a predetermined speed, the comb may be actuated at a somewhat faster linear speed, and the fabric or paper feeding rolls may 90 be actuated at a very much higher speed than that of the combing device.

The above condition is graphically illustrated in the modified form of the invention illustrated by Fig. 6, wherein it will be noted that the rovings 50 emerge from the rolls 22 and 19 in a somewhat flattened and spread condition, thereby forming the fibres into a sheet or substantially sheet form. In the modification, however, instead of passing the fibres over a spreader as 52 in Fig. 1, they may be fed over a support 83, Fig. 6. This latter construction may be preferable where economy of floor space is not a matter of importance, whereas the construction as 100 indicated in Fig. 1 may be employed where economy of floor space is of importance. In either case, however, the rovings are flattened out or formed into a substantial sheet form between the roving feeding means and the combing device; and when the combing device is moved at a speed relatively greater than the feeding rolls 22 and 19, the sheet 105 of fibres, as graphically illustrated in Fig. 6, will be attenuated somewhat into the condition indicated at G, where it will be noted, the sheet of fibres has been elongated, drawn out, or drafted, as it may be called. When the attenuated sheet of fibres G pass between the nip of the rolls 10 and 13, the ends 110 of the fibres engage the adhesive surface of the fabric or paper, which tends to pull them lengthwise at the speed of the paper feed, which is preferably much higher than that of the combing device, so that the partially-attenuated sheet of fibres G becomes further attenuated, as graphically indicated at H, and laid substantially parallel longitudinally of and upon the adhesive surface 115 of the fabric or paper to be reenforced. Of 120

course, where two such fabrics are employed, one upon the other, the attenuated sheet of fibres will occupy a position between the two fabrics of sheets.

- 5 The feed of the rovings is relatively slow, while the feed of the fabric or paper to which the fibres of the rovings are applied, is relatively high, so that the large mass of fibres presented by the rovings become attenuated and thinned out or drawn out to the desired extent as they are applied to the adhesive surface of the fabric or paper to be reenforced. The ratio of this speed of the rovings and paper, and consequently the attenuation of the sheet of fibres, may be varied, and the output of the machine may be increased almost indefinitely.
- 10 Changes and alterations in the details of construction may be made within the true scope of the invention, as defined by the claims.

What is claimed is:—

1. In a machine of the character described, the combination of means for feeding a paper strip to be reenforced, means for feeding unspun fibres for application to the paper strip, means for attenuating the unspun fibres and placing them under tension on the paper strip, including a series of 25 combs movable in different paths, and means for guiding the upper run of the combs along an oblique path to facilitate the projection of the comb teeth into engagement with the fibres, and withdrawing the teeth 30 therefrom.

2. In a machine of the character described, the combination of means for feeding a paper strip to be reenforced, means for feeding unspun fibres for application to the 35 paper strip, means for attenuating the unspun fibres and placing them under tension on the paper strip, including a series of combs movable in different paths, and means for guiding the upper run of the combs along a path disposed at an angle to the direction in which the fibres leave the combs to facilitate the stripping of the fibres from the comb teeth.

3. In a machine of the character described, the combination of rolls for feeding a paper strip to be reenforced, means for feeding unspun fibres for application to the paper strip, and means for placing the unspun fibres in an attenuated condition on the paper strip, including a series of combs movable along an endless path having an upper and a lower run, and one of said paper feed rolls being positioned near an end of the upper run of the combs for the passage of the fibres over the roll and elevated above the plane of the upper run of the combs sufficiently to pull the fibres out of engagement with the comb teeth as the combs approach the end of their upper run.
4. In a machine of the character described,

the combination of means for feeding a paper strip to be reenforced, means for feeding unspun fibres for application to the paper strip, means for applying the fibres to the paper strip, including a series of combs, a depressor for retaining the fibres in engagement with the teeth of the combs, and a doffer for disengaging the fibres from the comb teeth.

5. In a machine of the character described, 75 the combination of means for feeding a paper strip to be reenforced, means for feeding unspun fibres for application to the paper strip, and means for applying the fibres to the paper strip under lengthwise tension, including a series of combs, doffing means to disengage the fibres from the teeth of the combs, and rotatable cam means for moving the doffing means to the doffing position.

6. In a machine of the character described, the combination of means for feeding a paper strip to be reenforced, means for feeding unspun fibres for application to the paper strip, and means for applying the fibres to the paper strip, including a series of combs, doffing means to disengage the fibres from the teeth of the combs, cam means for moving the doffing means to the doffing position, and other cam means in the path of the doffing means to move them from the doffing position.

7. In a machine of the character described, 100 the combination of rolls for feeding a paper strip to be reenforced, rolls for feeding a series of rovings of unspun fibres towards the paper strip, means between the feed rolls for the rovings and paper respectively for attenuating the unspun fibres and applying them in a thin sheet to the paper strip, and means for advancing the fibres as they leave the feeding rolls over a path substantially greater in length than the distance between the fibre feeding rolls and the attenuating means to facilitate drawing 105 out the fibres.

8. In a machine of the character described, the combination of paper feeding means for feeding a paper strip to be reenforced, fibre feeding means for feeding a sheet of unspun fibres towards the paper strip, means between the respective feeding means for attenuating the unspun fibres and placing them on the paper strip, and means for advancing the fibres from the fibre feeding 115 means toward the paper feeding means over a path substantially greater in length than the distance between the respective feeding means to facilitate drawing out the fibres by the attenuating means.

9. In a machine of the character described, the combination of means for feeding a paper strip to be reenforced, means for gripping unspun fibres and feeding them for application to the paper strip, means be- 120

- tween the respective feeding means for the paper and fibres for attenuating the fibres and applying them to the paper strip, and means for advancing the fibres as they leave the gripping means over a path substantially greater in length than the distance between the gripping means and the point where the fibres are secured to the paper strip to promote attenuation of the fibres 10 while passing over said path.
10. In a machine of the character described, the combination of means for feeding a paper strip to be reenforced, and means for feeding unspun fibres for application to the paper strip, including an endless carrier having combs thereon for attenuating the fibres and tensioning the same as they are applied to the paper strip.
11. In a machine of the character described, the combination of means for feeding a paper strip to be reenforced, means for feeding unspun fibres towards the paper strip, means for attenuating the unspun fibres and applying them to the paper strip under tension, and a spreader for engaging the fibres and spreading them into sheet form after leaving the fibre feeding means.
12. In a machine for reenforcing a paper fabric, the combination of means for feeding a paper fabric having an adhesive surface to be reenforced, means for attenuating a sheet of reenforcing filaments and delivering them to the adhesive surface of the paper fabric, and doffing means for detaching the filaments from the attenuating means for delivery to the adhesive surface of the paper fabric.
13. In a machine for reenforcing a paper fabric, the combination of means for feeding a paper fabric having an adhesive surface to be reenforced, means for attenuating a sheet of reenforcing filaments and delivering them to the adhesive surface of the paper fabric, doffing means for detaching the filaments from the attenuating means, and automatically-operating means for causing the doffing means to free the filaments and effect delivery thereof to the paper fabric.
14. In a machine for reenforcing a paper fabric, the combination of means for feeding a paper fabric to be reenforced, means for feeding reenforcing filaments for application to the paper fabric, and a spreader positioned to provide a path of travel between the filament feeding means and the paper fabric greater than the length of the individual filaments and adapted to spread the filaments into a sheet for application to the paper fabric.
15. An apparatus of the character described, comprising, in combination, means for feeding fabric to be reenforced, and means for applying unspun fibres to the fabric including a comb carrier having teeth projecting outwardly therefrom, means to feed said comb carrier along different runs, and a doffing device for thrusting the fibres from the teeth of the comb pass from their upper run to their lower run.
16. An apparatus of the character described, comprising, in combination, means for feeding fabric to be reenforced, a carrier having a series of combs mounted thereon, means for feeding said carrier to cause the combs progressively to project up through a sheet of fibers and to conduct the same toward said fabric, a doffing device for each of said combs, and means automatically to operate said doffing devices to thrust the fibres from said combs as they approach the fabric to be reenforced.
17. An apparatus of the character described, comprising, in combination, means for feeding fabric to be reenforced, and means for feeding unspun fibres to said fabric including a carrier having a series of combs thereon, doffing devices for said combs, and means for automatically operating the same to doff the fibres from the combs as the latter approach the fabric.
18. An apparatus of the character described, comprising, in combination, a pair of rolls for feeding fabric to be reenforced, a pair of feeding-in rolls for feeding reenforcing filaments into the machine, and means to conduct the filaments from said feed rolls to the fabric including a comb carrier having a series of combs thereon, doffing bars associated with said combs, and means automatically to elevate said bars relatively to said combs to doff the filaments therefrom as they approach the fabric to be reenforced.
19. In a machine for reenforcing a paper fabric, the combination of means for feeding a paper fabric to be reenforced, rolls for feeding reenforcing filaments for application to the paper fabric, a spreader over which the filaments pass to and positioned to provide a path of travel between the feeding rolls and paper fabric greater than the length of the individual filaments and adapted to even out or spread the filaments into a sheet, and means for attenuating the spread sheet of filaments and delivering the filaments to the paper fabric.
20. In a machine for reenforcing a paper fabric, the combination of means for feeding a paper fabric to be reenforced, rolls for feeding reenforcing filaments for application to the paper fabric, a comb device for attenuating the filaments and delivering them to the paper fabric to reinforce the same, and a spreader between the rolls and comb device for spreading the filaments into a sheet.
21. In a machine of the character described, the combination of means for feeding a fabric to be reenforced by unspun fibres, feeding means for feeding unspun fibres for application to the fabric to be

reenforced, and means between the fibre feeding means and source of fibre supply for distributing the draft or pull of the feeding means through the fibres substantially to the source of supply.

22. In a machine of the character described, the combination of means for feeding a fabric to be reenforced, feeding means for feeding unspun fibres for application to the fabric to be reenforced, and draft distributing devices arranged at distances apart not more than the average length of the unspun fibres between the feeding means and source of fibre supply for transmitting the draft or pull of the feeding means.

23. In a machine of the character described, the combination of means for feeding a fabric to be reenforced, feeding means for moving a series of unspun fibre rovings for application to the fabric, and a plurality of devices constructed and arranged to engage the rovings at intervals between the roving feeding means and source of supply for distributing the pull of the roving feeding means throughout the length of the rovings.

24. In a machine of the character described, the combination of means for feeding a fabric to be reenforced by longitudinally-extending unspun fibres, feeding means for feeding an untwisted roping of fibre for application of the fibres to the fabric, and rolls constructed and arranged to engage the roping of fibre at intervals of less length than the average length of the fibres between the feeding means and source of roping supply to prevent the roping being elongated or drawn out by the pull of the roping feeding means.

25. In a machine of the character described, the combination of means for feeding a fabric to be reenforced by longitudinally-extending unspun fibres, feeding means for feeding an untwisted roping of fibre for application of the fibres to the fabric, rolls constructed and arranged to engage the roping of fibre at intervals of less length than the average length of the fibres between the feeding means and source of roping supply to prevent the roping being elongated or drawn out by the pull of the roping feeding means, and means between the roping feeding means and fabric feeding means for laying the roping into substantially sheet form.

26. In a machine of the character described, the combination of means for feeding a fabric to be reenforced by longitudinally-extending unspun fibres, feeding means for feeding an untwisted roping of fibre for application of the fibres to the fabric, and rolls constructed and arranged to engage the roping of fibre at intervals of less length than the average length of the fibres between the feeding means and source

of roping supply to prevent the roping being elongated or drawn out by the pull of the roping feeding means, and means for attenuating the roping of fibre between the roping feeding means and the fabric to be reenforced.

27. In a machine for reenforcing paper, the combination of paper feeding means for feeding paper to be reenforced, feeding means for feeding reenforcing filaments for application to the paper, means between the filament feeding means and the source of supply for distributing the draft or pull of the filament feeding means through the filaments to the source of supply, and a spreader for spreading the filaments as they are advanced for application to the paper.

28. In a machine for reenforcing paper, the combination of paper feeding means, means for pulling reenforcing filaments in the form of rovings from a source of supply for application to the paper, means between the source of supply and pulling means for distributing the draft or pull through the filaments to the source of supply, and means for spreading the rovings of filaments into sheet form for application to the paper.

29. In a machine for reenforcing paper, the combination of paper feeding means, means for pulling reenforcing filaments in the form of rovings from a source of supply for application to the paper, means between the source of supply and pulling means for distributing the draft or pull through the filaments to the source of supply, and means for spreading the rovings into sheet form and attenuating the sheet of filaments for application to the paper to be reenforced.

30. In a machine for reenforcing paper, the combination of paper feeding means, means for pulling reenforcing filaments in the form of rovings from a source of supply for application to the paper, means between the source of supply and pulling means for distributing the draft or pull through the filaments to the source of supply, a spreader for spreading the rovings into a sheet, and a comb device for attenuating the sheet of filaments and delivering it to the paper fabric.

31. In a machine for reenforcing a fabric by unspun fibres, the combination of means for feeding the fabric to be reenforced, means for applying an adhesive to a surface of the fabric, feeding means for moving a series of rovings of fibre from a source of supply for application to the surface of the fabric, draft transmitting devices arranged to engage the rovings at intervals between the roving feeding means and the source of roving supply to prevent the rovings being elongated and broken, and means for delivering the fibres of the rovings to the adhesive surface of the fabric.

32. In a machine for reenforcing a fabric

- by upspun fibres, the combination of means for feeding the fabric to be reenforced, means for applying an adhesive to a surface of the fabric, feeding means for moving a series 6 of rovings of fibre from a source of supply for application to the surface of the fabric, draft-transmitting devices arranged to engage the rovings at intervals between the roving feeding means and the source of roving supply to prevent the rovings being elongated and broken, and means for distributing the roving in the form of a sheet and applying the sheet to the fabric in an attenuated condition.
- 15 33. In a machine of the character described, the combination of paper feeding means, means for feeding a plurality of fibre rovings for application of the fibres to the paper, rolls bearing on the rovings of fibre 20 at intervals not greater than the length of the fibres of the rovings between the roving feeding means and the source of supply constructed and arranged to transmit the pull of the feeding means longitudinally of the 25 rovings, means for forming the rovings into substantially a sheet of fibres when they are delivered by the roving feeding means and applying the sheet of fibres in attenuated condition longitudinally on the surface of 30 the paper.
34. In a machine of the character described, the combination of means for feeding a fabric to be reenforced by longitudinally extending unspun fibres, means for 35 moving a series of rovings from sources of supply for application of the unspun fibres thereof to the fabric, rolls which bear upon the rovings at intervals of less distance apart than the length of the fibres in the rovings
- between the moving means and the sources 40 of supply and arranged to be rotated by the pull of the fibres between consecutive rolls.
35. In a machine for reenforcing paper by the application of unspun fibres thereto, feed rolls for feeding the web of paper, a 45 combing device having pins or teeth which engage the sheet of unspun fibres and move it toward delivery position, and lifter bars for disengaging the fibres from the pins or teeth of the comb when the sheet of fibres is 50 sufficiently attenuated.
36. In a machine for reenforcing paper by the application of unspun fibres thereto, feed rolls for feeding the web of paper, a 55 combing device having pins or teeth which engage the sheet of unspun fibres and move it toward delivery position, lifter bars for disengaging the fibres from the pins or teeth of the comb when the sheet of fibres is 60 sufficiently attenuated by the pull of the paper web, and means for raising the lifter bars.
37. In a machine for reenforcing paper by the application of unspun fibres thereto, feed rolls for feeding the web of paper, a 65 combing device having pins or teeth which engage the sheet of unspun fibres and move it toward delivery position, lifter bars for disengaging the fibres from the pins or teeth of the comb when the sheet of fibres is 70 sufficiently attenuated by the pull of the paper web, and means for depressing the lifter bars.

In testimony whereof, we have signed
out names to this specification.

CHARLES H. HOWARD.
LEWIS SHARP.
